PICKER STICK CHECK APPARATUS

Frank L. Goodnough, Rte. 2, Galax, Va., and Douglas D. Goodnough, Burlington, N.C. (P.O. Box 386, Swopeville, N.C.)

Filed Nov. 16, 1956, Ser. No. 622,639

13 Claims. (Cl. 139—169)

This invention relates to looms and more particularly to an apparatus for retarding and checking the movement of a picker stick which may be assembled on the lay of a loom for receiving the impact of a picker stick and to yieldably check the movement thereof.

In the conventional loom a shuttle, carrying the weft yarn, is propelled across the loom in flight under the impact of a blow received from a rapidly moving lever referred to as a picker stick. When the picker stick is accelerated rapidly by means of a cam control and linkage connection, the stick imparts momentum to the shuttle which shuttle will be driven in flight across the loom, decelerating to a stop at the far side under the action normally of a spring-loaded friction box. The decelerating shuttle will strike a picker stick at the far side of the loom with sufficient momentum to pivot the picker stick in the direction of shuttle movement. A leather check strap will normally limit the final angle of travel of the picker stick. Repeated impact of the shuttle driving the picker stick outwardly subjects check straps to considerable wear and frequent adjustment and replacement is necessary. Furthermore, since picker stick check straps are made of resilient material, such as leather, there is a tendency for the check strap to stretch or become distorted gradually or lose some of its modulus of elasticity with prolonged use. Also, due to the varying changes in atmospheric conditions within a weave room a leather check strap will tend to offer varying degrees of impact resistance which eventually may be evident in irregularities which appear in the finished woven material.

There is also a tendency when a shuttle is propelled across the loom under the impact of the rapidly moving picker stick for the forward end of the shuttle to elevate slightly from its projected path whenever the picker stick travels beyond a predetermined vertical position. Frequently shuttle speed may be reduced or the shuttle may fail to complete its flight. When this occurs, that is, when the shuttle has not boxed by the time the lay swings forward to drive the weft yarn in position, there is danger that the shuttle will be swept forward by the reed and pushed into the fill of the cloth. Many warp yarns may be broken and irreparable damage done to the fabric when a smash occurs, necessitating a relatively long shutdown for withdrawing and repairing the broken warp yarns.

Therefore, an object of the present invention is to provide a picker check apparatus for resiliently checking the speed of a picker stick and limiting the extent of picker stick displacement.

Yet another object of the present invention is the provision of a picker stick check mechanism for adjustably limiting the arcuate displacement or angular displacement of a picker stick.

A further object of the present invention is to provide an adjustable picker stick check mechanism which may be readily attached to the lay of a loom thereby eliminating the use of flexible picker stick check straps.

Still another object of the present invention is to pro-

2

vide a combination adjustable picker stick check mechanism and friction box for limiting the displacement of and for controlling the speed of picker stick travel.

Still another object of this invention is the provision of a picker stick check mechanism suitable for attachment to a conventional loom that will be adjustable between limits to control positively the maximum angular displacement of a picker stick.

More specifically, an object of the present invention is to provide a picker stick check strap eliminator for application to a loom which comprises a framework which may be releasably fastened to the box of a loom, a shaft secured directly to the framework and projecting transversely thereto to support a picker stick engaging arm pivotally mounted thereon, a pair of stops associated with the picker stick engaging arm to limit the extent of pivotal movement of the arm in opposite directions, the picker stick engaging arm having means associated therewith for normally urging the arm against one of the stops to receive and absorb the impact energy of the picker stick, a friction box mounted on the framework in advance of the picker stick engaging arm with the box having a stationary padded guide member mounted thereon and a laterally pivotable padded member in spaced relation to the fixed member with means associated with the pivotable padded member for urging it into cooperative relation with the stationary padded member to partially impede picker stick travel.

Other objects and many of the attendant advantages of this invention for decelerating, guiding and limiting picker stick movement will become more readily apparent to those skilled in this art during the course of the following detailed description, taken in conjunction with the accompanying drawings wherein like characters of reference refer to corresponding parts throughout the several views, and wherein:

Fig. 1 is a fragmentary side elevational view of a loom illustrating the upper portion of a picker stick and lay thereof, depicting one form of the present invention in combination therewith;

Fig. 2 is a longitudinal sectional view taken substantially along the plane of section line 2—2 of Fig. 1;

Fig. 3 is a partial transverse sectional view taken substantially along the plane of section line 3—3 of Fig. 1;

Fig. 4 is a partial perspective view of the yieldable picker stick check mechanism per se of Fig. 1;

Fig. 5 is a fragmentary side elevational view of a loom illustrating a shuttle, picker stick and lay thereof showing a modified form of the present inventive concept;

Fig. 6 is a longitudinal horizontal sectional view taken substantially along the plane of section line 6—6 of Fig. 5;

Fig. 7 is a transverse sectional view taken substantially along the plane of section line 7—7 of Fig. 5;

Fig. 8 is an enlarged perspective view of the picker stick check device per se illustrated in Fig. 5; and

Fig. 9 is an exploded view, in perspective, illustrating several components of the pivotable picker stick check arm.

Referring to the drawings and more particularly to Figs. 1 and 2, there is disclosed therein one unit of a pair of mechanisms embodying the present invention as mounted to the left side of a loom at the base of the loom lay 10 within which a shuttle (not shown) is reciprocated rectilinearly upon actuation of picker stick 12 which picker stick is actuated by means of cam control and related lever mechanisms that are not shown as they are familiar in the art. The lay end 13 is encompassed by a leather bumper strap 14 adjacent to which the picker stick 12 will rest in one extreme position. A picker stick check supporting framework 15 is securely mounted to the lay base by an attaching bracket member 16 in which there are longitudinally spaced slotted open-

ings 17 for receiving fastening bolts 18 therein. Projecting adjacent to one end of the bracket member 16 is an arm 19 that extends downwardly from the bracket member and to the left. A reinforcing strut member 20 is welded at a position intermediate the length of the bracket member 16 and extends to a position intermediate the length of the arm 19. A stub shaft 21 is welded at one end in the medial portion of the bracket 16 and extends vertically downward to a free end at which end a thread is provided for threaded engagement by the nut 22.

A pair of projecting ears 24 and 25 extends transversely from the arm 19 in spaced angular relation with respect to the shaft receiving opening 27 in the arm 19. Each of the ears 24 and 25 receive in threaded engagement an adjustable limit stop 28 and 29, respectively, with each stop having a locking nut 30 thereon to lock the stops in the desired position.

A shaft 31 having threaded ends is received in the arm opening 27 and extends transversely therefrom to receive a sleeve bearing 32 thereon, one end of the bearing 32 has an enlarged shoulder 33 in which a spring-end receiving blindhole 34 and threaded set-screw receiving opening 37 for the set-screw 38 are provided. An axial passageway 35 extends from one end of the shaft 31 to communicate with a transverse passageway 36 in order to transmit a suitable lubricant to the bearing sleeve 32. A lubricant fitting 37' is threadably connected to the shaft end to admit a suitable lubricant into the passageway 35.

A picker stick check arm 39 is pivotally supported on the sleeve bearing 32 through the hollow cylindrical hub 40 which extends transversely to the arm 39 and has a diameter substantially that of the sleeve bearing shoulder 33. One end of the hub 40 reaches toward the shoulder 33 and the other end abuts against the side extension 41 integral with the arm 39. Although hub 40 may be integrally cast with the arm 39 it is shown as a separate element in Fig. 3. Pivotal resilience of the arm 39 is supplied by means of a helical coil spring 43 which encircles the periphery of hub 40 and reaches transversely from the spring hook end 44 that engages a flange skirt on the arm 39 across the hub 40 to enable the other hook end 45 of the spring into the opening 34 in the bearing sleeve shoulder 33. The threaded free ends of shaft 31 receive fastening nuts 46 to retain the picker stick check arm components in operative relation.

Adequate torsional resilience to resist picker stick impact through angular displacement of the picker stick arm between the limit stops 28 and 29 may be provided simply by rotating the bearing sleeve 32 in the desired direction with the spring ends secured against the arm flange and in the hole 34 to increase or to decrease the resistance of the spring 43. By tightening the set-screw 38 against the shaft 31 relative rotation of the sleeve and shaft may be eliminated.

Depending upon the specific space requirements of each loom the arm 39 may be modified so that the projecting bumper portion 47 may extend from the main portion of the arm a desired distance. A leather pad 48 or other suitable padding material may be secured to the face of the bumper member to receive the direct blow of the picker stick as it strikes the arm 39. It will be apparent that the picker stick check arm will be positioned initially against a forward stop 29 to absorb the impact of the picker stick 12 and sufficient resistance will be offered by the spring 43 to prevent the check arm 39 from striking against the rear limit stop 28 with any appreciable force.

To reduce picker stick impact and also to limit for displacement of the picker stick, one element of a friction attachment is pivotally mounted on the bracket shaft 21 in the form of lever brake arm 50 turned at one end to form a shaft-receiving sleeve 51. The free end of the arm is engaged by a vertical leaf spring 53 fastened at one end by means of the bolt 54 to the side of the loom

lay to normally urge the arm 50 into the path of picker stick travel and against the end stop 54'. End stop 54' is mounted for pivotal movement on the stud 55 which is retained on bracket 56 that is fastened to the lay. Stop 54' has an elongated arm 57 preferably made in the form of a profile cam or eccentric to ride on the fixed follower 58 which is mounted on the loom in spaced relation to the stop 54'. The rate and extent of displacement for arm 50 will be limited upon the arm 57 engaging the stop 54'.

A padded surface 59 reaching longitudinally along the brake arm 50 in the path of picker stick travel is supported against a plate 60 which plate is adjustably secured by means of threaded bolts 61 that extend from the plate transversely to the arm 50 and are fastened thereto intermediate the arm length. Transverse adjustment of the plate 60 may be accomplished by means of the fastening nuts 63 and 64 which engage opposite sides of arm 50 and are brought into a clamping fit against the arm.

Although in some instances it may be possible to use the single brake arm 50, it is preferred that a second stationary arm 65 be used in combination with the pivotable arm 50. Arm 65 is fastened by the bolt 66 to the vertical bracket 67 which bracket is fastened to the lay by means of the bolt 68. Arm 65 reaches longitudinally in spaced lateral relation to the arm 50 and terminates in a vertical reach 69 which has a horizontal flange portion with an opening 71 therein to receive a fastening bolt 72 for securing the arm 65 to the lay. A friction pad 73 is mounted on plate 74 by means of screws 75. Plate 74 is secured to the base angle plate 76 through slotted openings 77 which will receive the fastening screws 78 for lateral adjustment of the plate. The normal transverse opening or gap between the padded surfaces 59 and 73 is preferably slightly less than the width of the picker stick thereby requiring some lateral movement of the arm 50 when the picker stick passes between the padded surfaces.

In operation, as the picker stick 12 pivots from left to right, in the extreme right position the picker stick will extend beyond the padded surfaces 59 and 73. As the shuttle moves to the left and strikes the picker stick, the impact will drive the stick to the left sharply. To pass through the transverse gap between pads 59 and 73 the picker stick will engage the padded surfaces 59 and 73 which are sufficiently curved to guide the picker stick into the gap. The brake arm 50 will be forced to pivot outwardly under the resistance of spring 53. Ultimately the retarding cam action of arm 57 on the follower 58 will resist further outward movement of the arm. As the momentum of the picker stick is partially reduced in passing through the picker stick friction box, it will next engage the padded surface 48 on the picker stick check arm 39 and the arm will be pivoted from the right position stop 29 against the left stop 28. By adjusting the tension of spring 43, the energy of impact of the stick may be absorbed sufficiently by the spring to reduce the direct shock and act as a shock absorber. In the advance stroke, with the shuttle, not shown, at the left side of the lay, the picker stick motion to the right will be retarded as the stick reenters the picker stick friction box from left to right. With the linear travel of the picker stick being limited each time to a predetermined vertical position the shuttle will be driven by the picker stick motion until the picker stick reaches approximately the vertical position. Subsequently, the picker stick will complete its stroke to the right beyond the friction box. In this manner, the shuttle will not be acted upon by a downward force component from the picker stick to depress the rear and raise or tilt the forward end of the shuttle.

There is shown in Figs. 5 through 9 a modification of the invention in which a pivotable picker stick check apparatus 80 is employed per se as attached to a loom

lay 81 to retard the movement of the picker stick 82 to the left after it has been struck by the shuttle 83 in its movement to the left. The bracket 84, substantially similar to the bracket 15, has an arm 85 welded to the bracket 84 with the arm 85 reaching downwardly toward the left. A reinforcing strut member 86 is fastened at its ends by welding to a position intermediate the length of the arm 85 and the bracket 84.

The bracket 84 has spaced slotted openings 87 in the flange 88 for slidable adjustment relative to the fastening bolts 89 which are retained in the bottom of the lay to secure the bracket in position. A shaft 90 having a threaded end 91 is passed through an opening 92 in the arm 85 and reaches transversely. A bearing sleeve 93 encircles the shaft 90 and over the bearing sleeve at one end there is a spring retaining ring 94 fastened on the sleeve bearing by means of the setscrew 95. At least one spring end receiving opening 96 is drilled in the periphery of the ring 94.

A picker stick check arm 97 having a central hub portion 98 about which a helical coil spring 99 is mounted on the bearing sleeve 93 for pivotal action between limits. One end of the hub portion 98 is in spaced axial relation with the ring 94 providing sufficient clearance therebetween to prevent locking of the arm 97 during pivoting. Spring 99 on the hub portion 98 will project into the annular cavity 100 formed by the hub portion 98 and the partial skirt 101 flaring outwardly from the arm 97. One end 102 of the spring 99 may be inserted into the spring hook opening 96 and the other hook end 103 of the spring will engage the skirt 101. Suitable spring resilience or tension may be obtained by rotating the ring 94 with the spring hooked thereon and locking the ring in position.

Sleeve bearing 93 may be provided with a head 105 at one end to facilitate adjustment of spring tension as will be described. Also mounted on the shaft 90 is a pair of angle plates 106 and 107 which have inwardly projecting limit portions 108 against which the edges of the skirt on the picker stick arm 97 will strike in pivotal movement. The bolt head 109 on the end of the shaft is tapped to threadably receive a lubricating fitting 110 for transmitting lubricant to the axial passageway 111 in the shaft 90. Lubricant from the passageway 111 will be admitted through the transverse opening 112 in the shaft and through the communicating opening 113 in the bearing to lubricate the bearing surface of the picker stick check arm.

The picker stick check arm 97 of the embodiment illustrated is substantially planar and is provided at its free end with a padded member 115 against which the picker stick 82 will strike in moving to the left before striking the leather band 116 at the lay end 117. To provide tension adjustment in spring 99, the shaft fastening bolt 118 may be loosened and by rotating the head 105 of the bearing sleeve 93 relative to the shaft the ring 94, fastened by means of the set-screw 95 to the sleeve will provide the requisite tension to the spring 99 so as to normally urge the arm forwardly to engage the edge 108 of the forward stop 106 in the initial picker stick striking position.

In operation, as the shuttle 83 is reciprocated rectilinearly and in its movement to the left, it will strike the padded end 118' of the picker stick with sufficient momentum to force the picker stick to the left. The picker stick will strike the end of the picker stick check arm 115 and the arm will be forced to the left. The picker stick will continue moving to the left resisted by the action of the spring 99. It is desirable to have adequate spring tension so that a movement of the arm 85 will stop just prior to impact of the skirt flange with the rear stop 107. However, on occasion the back portion of the skirt flange may strike the stop 107 to positively limit rearward movement of the arm. It will be apparent that the end stops 106 and 107 may be readily

adjusted to whatever included angle of travel is desired by merely positioning the angle plates 106 and 107 relative to each other. When the picker stick 82 is moved to the right the arm 97 will be prevented from movement beyond the forward stop 106.

Obviously, many modifications and variations may be made in the construction and arrangement of the picker stick check arm and the other elements constituting the assemblage in light of the above teachings without departing from the real spirit and purpose of this invention. It is, therefore, to be understood that within the scope of the appended claims many modified forms of structure as well as the use of mechanical equivalents may be reasonably included and modifications are contemplated.

What is claimed is:

1. A picker stick check apparatus for a loom comprising a bracket for fastening the apparatus to the base of a loom lay, a picker stick check member supported by the bracket in the path of picker stick travel, said check member being displaceable between limits, resilient means for normally urging the check member to absorb picker stick impact at the terminal portion of picker stick travel, a picker stick swing gate pivotally mounted on the bracket in advance of said check member, a stationary member mounted in spaced lateral relation to the swing gate and to cooperate therewith to form a gap through which a picker stick will pass, said swing gate and said stationary member having padded picker stick contact portions thereon, and resilient means for normally urging said swing gate into juxtaposition with the stationary member whereby the picker stick terminal movement may be decelerated by passing between the swing gate and the stationary member and final impact may be absorbed by the check member.
2. A picker stick check apparatus for a loom comprising a bracket for fastening the apparatus to the base of a loom lay, a picker stick check member supported by the bracket in the path of picker stick travel, stops on said bracket to limit the movement of the check member, and resilient means for normally urging the check member against one of the stops and to absorb picker stick impact, a picker stick friction box mounted on the bracket comprising a swing gate resiliently mounted on the bracket in advance of said check member, a stationary member mounted in spaced lateral relation to the swing gate to form a gap therewith through which a picker stick will be admitted yieldingly, said swing gate and said stationary member having padded picker stick contact portions thereon, and resilient means for normally urging said swing gate into juxtaposition with the stationary member whereby the picker stick terminal movements may be retarded by passing between the swing gate and the stationary member and final impact may be absorbed by the check member.
3. A picker stick check apparatus for a loom comprising a bracket fastened to a loom lay, a shaft supported by the bracket, a padded picker stick check arm pivotally mounted on the shaft, adjustable stops for limiting the angle of check arm movement, spring means normally urging the check arm toward one limit stop, a picker stick friction means mounted in spaced relation to the check arm, said friction means including a padded friction plate mounted to pivot about a vertical axis out of the path of picker stick travel upon impact by a moving picker stick, and means to yieldably resist the pivotal displacement of the friction plate.
4. A picker stick check apparatus for a loom comprising a bracket fastened to a loom lay, a shaft supported by the bracket, a padded picker stick check arm pivotally mounted on the shaft, stops for limiting the angle of check arm movement, means for normally urging the check arm toward one limit stop and for absorbing impact energy of a picker stick, a picker stick friction box mounted in spaced relation to the check arm on the

bracket, said friction means including a padded friction plate mounted to pivot about a vertical axis upon impact by a picker stick, and spring means to yieldably resist pivotal displacement of the friction plate.

5. A picker stick check apparatus for a loom comprising, in combination, a bracket fastened adjacent the terminal end of a loom lay, a shaft supported by the bracket, a picker stick check arm pivotally mounted at one end on the shaft for displacement in a vertical plane in the path of picker stick travel, the free end of the arm having an impact cushion pad thereon, a pair of adjustable stops supported on the bracket in spaced relation to limit angular check arm displacement, spring means normally urging the check arm against one of the stops, a gate arm pivotally mounted on the bracket for lateral displacement in a horizontal plane in advance of the check arm to partially check picker stick momentum, said gate arm having a reach of material of substantially high coefficient of sliding frictional resistance secured thereto, and means for yieldably resisting pivotal gate arm movement.

6. A picker stick check apparatus for a loom comprising, in combination, a bracket fastened adjacent the terminal end of a loom lay, a shaft supported by the bracket, a picker stick check arm pivotally mounted at one end on the shaft for displacement in a vertical plane in the path of picker stick travel, the free end of the arm having an impact cushion thereon, a pair of adjustable stops supported on the bracket in spaced relation to limit angular check arm displacement, spring means normally urging the check arm against one of the stops, a gate arm pivotally mounted on the bracket for lateral displacement in a horizontal plane in advance of the check arm to partially check picker stick momentum, said gate arm having a reach of material of substantially high coefficient of sliding frictional resistance secured thereto, resilient means for yieldably resisting gate arm pivotal movement, a guide wall having a reach of material similar to said material on the gate arm mounted in spaced lateral relation to the gate arm and providing an entrance gap for a picker stick, said gap being insufficient to permit free passage of a picker stick therethrough without forcing the gate arm to be displaced.

7. A picker stick check apparatus for a loom comprising, in combination, a bracket fastened adjacent the terminal end of a loom lay, a shaft supported by the bracket in the path of picker stick travel, a picker stick check arm pivotally mounted at one end of the shaft for displaceable movement in a vertical plane, a pair of stops for limiting pivotal movement of the check arm in both directions, means for normally urging the check arm against one of the stops and for yieldably resisting picker stick movement, a gate arm pivotally mounted on the bracket for lateral displacement in a horizontal plane in advance of the check arm to partially absorb picker stick momentum, said gate arm having a reach of frictional material secured thereto, and resilient means for yieldably resisting gate arm movement whereby upon picker stick movement the gate arm will be shifted laterally out of the path of the picker stick.

8. A picker stick check mechanism for looms comprising a bracket member, a shaft supported by said bracket member, a bearing on said shaft, a picker stick check arm pivotally mounted on said bearing, a pair of spaced stops supported by said bracket for limiting the pivotal movement of said arm in both directions, means normally urging said arm against one of said stops, said shaft having a passageway therein leading to said bearing, and a lubrication fitting supported by the shaft to communicate with the passageway.

9. A picker stick check apparatus for looms comprising a bracket fastened adjacent to the terminal end of a loom lay, a shaft supported by said bracket, a bearing on said shaft, a picker stick check arm pivotally mounted on said bearing, a pair of spaced adjustable stops sup-

ported on the bracket for limiting the pivotal movement of said arm in both directions, means normally and yieldably urging the check arm against one of said stops, said shaft having a passageway therein leading to the bearing, a lubrication fitting supported on the shaft and communicating with the passageway, said means including a sleeve encircling the shaft, means carried by the sleeve for retaining said sleeve in a selected rotated position on the shaft, a resilient member embracing said sleeve and including first and second end portions, said sleeve having a hole in one end for receiving the first end portion of said resilient member, a hook on the second end portion of said resilient member, and a skirt projecting from said arm for receiving said hook.

10. A picker stick check apparatus for looms comprising a bracket fastened adjacent to the terminal end of a loom lay, a shaft supported by said bracket, a bearing on said shaft, a picker stick check arm pivotally mounted on said bearing, a pair of spaced stops supported on the bracket for limiting the pivotal movement of said arm in both directions, means normally and yieldably urging said arm against one of said stops, said shaft having a passageway therein leading to the bearing, a lubrication fitting supported on the shaft and communicating with the passageway, said means including a sleeve embracing the shaft, means carried by the sleeve for retaining said sleeve in a selected rotated position on the shaft, a coil spring member embracing said sleeve and including first and second end portions, said bearing having a notch in one end for receiving the first end portion of said resilient member, a hook on the second end portion of said resilient member for engaging the check arm, a gate arm pivotally mounted on the bracket for lateral displacement in the horizontal plane in advance of the check arm to partially check picker stick momentum, said gate arm having a padded surface of frictional resistance material, resilient means for yieldably resisting pivotal gate arm movement, a stop for limiting gate arm displacement, a guide wall having a reach of material substantially similar to said material on the gate arm mounted in spaced relation to the gate arm providing an entrance gap for a picker stick arm, said gap being insufficient to permit free passage of the picker stick therethrough without urging the gate arm laterally.

45 11. A picker stick check apparatus in combination with a loom lay comprising a bracket member mounted on the loom lay, a shaft supported by the bracket member in the path of picker stick travel, a picker stick check arm for receiving picker stick impact, a pair of stops supported by the bracket for limiting angular displacement of the arm, said stops being adjustable relative to each other, and spring means normally and yieldably urging the arm against one of the stops.

55 12. A picker stick check apparatus comprising a bracket for fastening adjacent to the terminal end of a loom lay, a shaft supported by said bracket, said shaft having an axial passageway and a transverse opening communicating with the axial passageway, a sleeve bearing on said shaft, said sleeve bearing having an opening 60 in registry with the transverse opening, a ring mounted on the sleeve bearing, a picker stick check arm having at one end a hub portion for rotation on the shaft, said check arm having a skirt extending partially around the hub portion to form an arcuate cavity therebetween, the other end of the check arm having a padded surface for contacting a picker stick, said ring having means for locking the ring on the sleeve bearing, a coil encircling the hub portion and reaching into the cavity and having the spring ends retained with one end secured to the ring and the other end secured to the skirt, means on the bearing sleeve for rotating the sleeve relative to the hub portion to increase or decrease spring tension with the ring locked to the sleeve, and a pair of angle stops 65 adjustably supported by the bracket to limit pivoting dis-

placement of the check arm, said skirt contacting a stop in opposite directions of displacement.

13. A picker stick check apparatus comprising a bracket for fastening adjacent to the terminal end of a loom lay, a shaft supported by said bracket, a sleeve bearing on said shaft, a picker stick check arm having at one end a hub portion for rotation on the shaft, said check arm having a skirt extending partially around the hub portion to form an arcuate cavity therebetween, the other end of the check arm having a padded surface, a ring on the sleeve bearing axially spaced from the hub portion, said ring having means for locking the ring to the sleeve bearing, a coil spring encircling the hub portion and reaching into the cavity and having the spring ends retained with one end secured to the ring 15 and the other end secured to the skirt, means on the

bearing sleeve for rotating the sleeve relative to the hub portion to increase or decrease spring tension with the ring locked to the sleeve, and a pair of angle bracket stops supported by the bracket to limit angular displacement of the check arm, said skirt contacting a stop in opposite directions of displacement.
